UNITED STATES PATENT OFFICE.

IRA S. ELKINS, OF NEW YORK, ASSIGNOR OF ONE-HALF TO ETHEL C. HINE,
OF BROOKLYN, N. Y.

MOUTH-PIECE FOR CIGARETTES.

SPECIFICATION forming part of Letters Patent No. 249,165, dated November 8, 1881.

Application filed December 31, 1880. (No model.)

To all whom it may concern:

Be it known that I, IRA S. ELKINS, a citizen of the United States, residing in the city, county, and State of New York, have invented certain 5 Improvements in Mouth-Pieces for Cigarettes, of which the following is a specification.

The most important requirements of a mouth-piece for cigarettes are that it shall be very cheap—indeed shall cost very little, if anything, more than the tobacco it displaces; that it shall be very light, so that the weight of the cigarettes so provided shall not materially exceed that of cigarettes without mouth-pieces; that it shall be neutral as to taste and smell, and 10 not disagreeable to the user; that it shall be elastic and yielding to the teeth, so that the user may regulate by pressure the amount of opening through which the smoke passes; that it shall not readily absorb moisture, whereby 15 the paper wrapper of the cigarette would become wet and soft and the mouth-piece liable to break off; and, finally, that it shall add nothing to the diameter of the cigarette, as in such a case the cigarettes could not be neatly packaged in the usual way. So far as I am aware, 20 none of the various cigarette and cigar mouth-pieces hitherto invented have combined all of these advantages or requirements, or any considerable proportion of them, although some 25 30 advantages have been possessed by all.

The object of my invention is to provide a mouth-piece for a cigarette which possesses all of the requirements enumerated as above. To this end I cut from cork a cylinder having a diameter equal to that of the roll of tobacco in the cigarette for which the mouth-piece is destined, and of sufficient length to give the smoker a firm hold on it with his teeth or lips and leave enough free to form an attachment 35 to the cigarette. Through this cylinder I bore or cut a small hole, preferably in its axis, for the passage of the smoke. For the sake of economy I cut the ends of the cork off square, as all attempts to round or hollow a mouth-piece add to its cost, and are unnecessary. 40 This mouth-piece is attached to the cigarette by simply rolling the paper wrapper around both tobacco and mouth-piece and securing by paste or gum, the wrapper extending part of 45 50 the way over the mouth-piece, and the inclosed

portion of the latter taking the place of the tobacco at that end.

In the drawings which serve to illustrate my invention, Figure 1 is a partial longitudinal mid-section, taken through a cigarette provided with my improved mouth-piece; and Fig. 2 is an end view of the same. Both views are somewhat more than full size.

Let A represent the ordinary wrapper of a cigarette, and B the tobacco filling. C is the 60 mouth-piece, of cork, provided with an axial bore, a, for the passage of the smoke. I have shown the wrapper as extending over the mouth-piece for about one-third of its length, that being about the proportion preferred.

The mouth-piece might be slightly tapered toward the outer end; but there would be no advantage in this, and such a construction would add to the cost of making, which is a 65 very important consideration.

The weight and cost of the mouth-piece is very nearly compensated by the weight and cost of the tobacco displaced, and yet there is no loss to the consumer, as the tobacco displaced only forms a mouth-piece for the ordinary cigarette, and is not burned. Thus I provide a cigarette with a mouth-piece which possesses all of the advantages and requirements of a perfect mouth-piece, and adds only a trifle, 70 if anything, to the cost of the article.

A mouth-piece cut in this way from solid cork is cheaper than when formed of cork in any other way, and it is much stronger and tougher. It also possesses elasticity enough to enable the smoker to regulate the size of the 85 smoke-passage at will by pressure with his teeth. The nicotine from the tobacco is also prevented from reaching the mouth of the smoker.

In lieu of a paper wrapper a tobacco or other 90 wrapper may be employed.

I am fully aware that cigar and cigarette mouth-pieces have been made from cornstalk-pith, glass, wood, stems, fibers, compressed tobacco, rattan, &c.; but none of these possess 95 the characteristics of my invention. Tobacco-pipes of cork with cork-stems have also been proposed; but these are necessarily costly, and have no bearing on the manufacture of cigarettes. Cigar-holders of cork have also been 100

suggested; but these are not mouth-pieces connected to and forming part of a cigar or cigarette. They are not sold with the cigar or cigarette, but are intended to be used for a long time, therefore they may be hollowed out and shaped at considerable expense.

Having thus described my invention, what I claim is—

1. A mouth-piece for a cigarette made of solid cork, with a longitudinal bore through it, and having, substantially, a cylindrical form, substantially as and for the purposes set forth.

2. A cigarette comprising a wrapper, A, a roll or filling of tobacco, B, and a mouth-piece,

C, cut from solid cork, of the same size as the 15 tobacco-roll B, and provided with a smoke passage or aperture, a, the end of said mouth-piece being arranged to extend into the wrapper and to displace a portion of the tobacco, substantially as set forth.

In testimony whereof I hereunto subscribe my signature in the presence of two attesting witnesses, on the 10th day of December, 1880.

I. S. ELKINS.
